UNITED STATES PATENT OFFICE.

LOUIS SANDERS, OF NEW YORK, N. Y.

DESIGN FOR A BELT.

SPECIFICATION forming part of Design No. 33,844, dated January 1, 1901.

Application filed December 8, 1900. Serial No. 39,235. Term of patent 3½ years.

To all whom it may concern:

Be it known that I, LOUIS SANDERS, a citizen of the United States, and a resident of the city of New York, borough of Brooklyn, in the county of Kings and State of New York, have invented and produced a new and original Design for a Belt, of which the following is a specification, reference being had to the accompanying drawing, forming a part thereof, in which is represented a plan view of a belt embodying the features of my design.

The leading features of the design consist in an ornamentation simulating a collar located at the central or back portion of the belt.

The minor features of the design consist in the pointed lower central longitudinal edge of the belt, in lines which extend longitudinally of the belt below the collar ornamentation, the lower line conforming to the lower

longitudinal outline of the belt, while the upper line conforms to the outline of the upper edge of the belt and the lower outline of the collar ornamentation, and in a panel between the two lines at the central or back portion of the belt.

Having thus described my invention, I claim as new and desire to secure by Letters Patent—

The design for a belt herein shown and described.

In testimony whereof I have signed my name to this specification in the presence of two subscribing witnesses.

LOUIS SANDERS.

Witnesses:

J. FRED ACKER,
JNO. M. RITTER.
